UNITED STATES PATENT OFFICE

ISAIAK IRVIN KABLANOW, OF SANTA CRUZ, CALIFORNIA

EGG PICKER

Application filed May 5, 1931. Serial No. 535,239.

This invention relates generally to means for reaching into inaccessible places to retrieve objects therefrom, and particularly to a long-handled device operable to reach into inaccessible places in a chicken roost nest or the like in order to secure and retrieve eggs which would ordinarily be out of reach by hand.

It is an object of this invention to provide a device of the character described which is not only simple and inexpensive in construction and durable, and efficient in operation, but which handles the eggs and the like without danger of breaking the same, even though they may be located in far corners either above or below the roost.

These and other objects of the invention, its nature, and its composition and arrangement and combination of parts will be readily understood by anyone acquainted with the art to which this invention relates upon reading the following descriptions of the drawings, in which:

Figure 1 is a general side elevational view of the device of my invention.

Figure 2 is an elevational view taken from the left of Figure 1.

Figure 3 is a view similar to Figure 1, showing the closed position of the claws or fork.

Figure 4 is a horizontal sectional view looking downwardly approximately on the line 4-4 of Figure 1.

Referring in detail to the drawings, a preferred embodiment of the invention consists of a wooden handle 5 in the end of which is fixed a metallic rod 6 which is bifurcated on its upper end and provided with a pin 7 horizontally between the bifurcations 8. Vertically swingable upon the pin 7 is a three-talon fork or claw generally designated 9 which is constructed by twisting the legs of a U-shaped bar or wire so as to provide the twisted shank 10 having the loop 11 at its back portion. The legs of the wire or bar member are angularly and laterally directed as indicated at 12 above which positions they are forwardly and curvedly bent to provide the talons 13. The twisted shank is slightly pulled apart at 14 to receive the pin 7 and there is provided at the apex of the talons a

loop 15 to receive a cable 16, the function of which will be described. Some distance below the bifurcated portion and the pin 7 there is provided a fork 17 of the shape seen in detail in Figure 4 which is so formed as to have its bight portion 18 wrapped about the bar 6 and to have axially bent portions 19 which are then directed in a parallel manner to assume a generally horizontal position with a curvature centrally thereof as seen in the drawings. The fork 17 is so positioned that it properly cooperates with the talons of the swingable fork 9. Below the fork 17 there is a wire formation 20 which provides a vertically disposed loop 21 and a horizontally disposed loop 22 on opposite sides of the rod 6. Through the horizontally disposed loop 22, passes the cable 16. To the vertically disposed loops 21 there is fastened the lower end of a coiled spring 23 which at its upper end engages as at 24 in the loop 11 of the twisted portion of the fork 9. The spring 23 normally retains the fork 9 out of the sphere of action of the fork 17 as seen in Figure 2.

The lower end of the cable 16 is connected to a loop or eye 25 on a triangular trigger formed of wire or bars and provided with a looped hand-engaging portion 26. One angle of the triangular trigger 27 is formed with an eye 28 to be mounted pivotally upon a pin 29 secured to the side of the handle 5.

By this arrangement, movement of the loop portion 26 of the trigger 27 will cause the downward movement of the cable 16 and consequently the movement of the fork 9 in the direction of the fork 17 whereby an object within the sphere of action of the forks will be firmly grasped as seen at 30, wherein the object is an egg. It is a very simple matter to withdraw the device and to safely remove and retrieve the egg from an inaccessible part of a coop or roost.

It is to be definitely understood that it is not desired to limit the application of this invention to the particular modification set out herein to illustrate the principles thereof, and any change or changes may be made in structure and arrangement of parts consistent with the spirit and scope of the invention.

What is claimed is:

1. An egg-retriever or the like of the type described comprising a rod having a handle at one end and a bifurcation at the other end provided with a cross pin, a spring opened claw swingable on the pin, a stationary claw on the rod for cooperation with swingable claw, and flexible cable means to swing the swingable claw.
- 10 2. An egg-retriever or the like of the type described comprising a rod having a handle at one end and a bifurcation at the other end provided with a cross pin, a spring opened claw swingable on the pin, a stationary claw on the rod for cooperation with swingable claw, and means to swing the swingable claw, said means comprising a trigger lever pivoted on the handle and a flexible cable secured to the lever and the swingable jaw, the connections of the cable with the trigger lever and swingable claw being on the same side of the rod.
- 15 3. An egg-retriever or the like of the type described comprising a rod having a handle at one end and a bifurcation at the other end provided with a cross pin, a spring opened claw swingable on the pin, a stationary claw on the rod for cooperation with swingable claw, and means to swing the swingable claw, said means comprising a trigger lever pivoted on the handle and a cable secured to the lever and the swingable jaw, said claws being of twisted wire construction providing longitudinally bowed talons.
- 20 4. In testimony whereof I affix my signature.

ISAAK IRVIN KABLNOW.
